Patented Feb. 1, 1916.

UNITED STATES PATENT OFFICE.

ANTHONY V. WEBER, OF ST. LIBORY, ILLINOIS.

ROTARY ENGINE.

1,170,373.

Specification of Letters Patent.

Patented Feb. 1, 1916.

Application filed February 19, 1915. Serial No. 9,369.

To all whom it may concern:

Be it known that I, ANTHONY V. WEBER, a citizen of the United States, residing at St. Libory, in the county of St. Clair, State of Illinois, have invented certain new and useful Improvements in Rotary Engines; and I do hereby declare the following to be a full, clear, and exact description of the invention, such as will enable others skilled in the art 10 to which it appertains to make and use the same.

This invention relates to a rotary engine.

An object of the invention resides in the provision of a machine of this character by 15 means of which power may be developed by the actuation of the rotor caused by the expansion of steam.

A further object of the invention is to so construct the device that the rotor, during 20 its movement, will effectively pump the used steam from the casing.

With these and other objects in view, such as will appear as the description progresses, my invention comprises the combination and 25 arrangement of parts as set forth in and falling within the scope of the appended claims.

Referring to the drawing: Figure 1 is an 30 elevational view of my device. Fig. 2 is a vertical sectional view. Fig. 3 is a vertical sectional view taken at right angles to Fig. 2. Fig. 4 is an enlarged detail of the exhaust mechanism showing the position of the rotor when the exhausting of steam is 35 about to be completed. Fig. 5 is a fragmental detail of a portion of a rotor, showing the arrangement of the blocks for preventing the escape of the steam between the rotor and the casing. Fig. 6 is a section on line 40 6—6 of Fig. 2.

Referring to the drawing wherein like parts are indicated by like characters throughout the several views:—My device comprises a substantially cylindrical casing 45 1 supported on a suitable base 2 in which is rotatably mounted, on a shaft 3 concentric with the casing, a rotor 4. This rotor consists of two substantially semi-cylindrical members 5 and 6 which are of lesser diameters than the casing 1 and which are eccentrically mounted on the shaft 3 so that projecting portions 7 and 8 are formed. The edge of each of these projecting portions is adjacent the inner face of the casing 1 and 50 in order that the steam may be prevented

from escaping between this edge and the casing I have provided a spring pressed block 9 which is normally projected outwardly and bears against the inner face of the casing. In order that the steam may be prevented 60 from escaping between the ends of the sections 5 and 6, I have mounted on each of the sections similar spring pressed blocks 10 which bear against the inner face of the ends of the casing 1. 65

In order that the rotor may be actuated I have provided a plate 11 which extends in through the casing 1 and normally bears against the face of the adjacent section 5 or 6 of the rotor. This plate 11 extends completely across the rotor and contacts with the inner faces of the ends thereof and is provided with a longitudinally extending hole 12. On the outer end of this plate is a piston 13 which is normally pressed downwardly, so as to maintain the inner face of the plate 11 in contact with the rotor, by a coil spring 14 operable in a cylinder 15. 70 75

In order that the hole 12 may be normally closed I have provided a gravity valve 16 80 mounted on the piston 13 beneath a spider 17. In the upper end of the cylinder 15 is formed an exhaust port 18. To one side of the plate 11 an inlet port 19 is provided.

Assuming that the parts are in the position shown in Fig. 2 the steam is injected 85 into the casing 1 between the plate 11 and the abrupt face 20 of the adjacent projection 8. The expansion of this steam exerts force against the face 20 and causes the movement 90 of the rotor until the abrupt face 21 of the projection 7 passes the plate 11 at which time the same action will take place against this face 21 of the projection 7. As soon as the passing of the projection 7 beyond the 95 plate 11 occurs the exhaustion of the steam, which has been previously injected between the plate 11, and the face 20 of the projection 8, begins. As this projection 8 moves toward the plate 11 the steam is forced 100 through the hole 12 therein because of the fact that the space between the section 5 of the rotor and the casing becomes gradually less. The forcing of the steam through the hole 12 unseats the valve 16 and forces the 105 steam from the port 18, at the same time the riding of the plate 11 on the curved face of the section 5 causes the piston 13 to move outwardly. This cycle of operation is repeated and thus while the steam is being in- 110

jected into the casing to one side of the rotor the spent steam on the other side of the rotor is being ejected.

From the foregoing description it will be seen that I have provided a rotary engine which will be very simple in construction and which will be operated by the expansion of steam. I have so constructed the engine that novel mechanism for exhausting the spent steam is provided.

While I have illustrated and described a particular embodiment of my invention, I have merely done so for the sake of convenience and I do not wish to be limited to that particular embodiment as it is obvious that numerous changes may be made in the details of construction thereof without in any way departing from the spirit of the invention or exceeding the scope of the appended claims.

What I claim is:—

1. In a rotary engine, a casing, a rotor mounted therein having gradually increasing spaces to the opposite sides thereof between itself and the casing, means for conveying steam to one of said spaces, a plate slidably mounted within the casing and bearing against the face of the rotor, the said plate having a hole extending outwardly therethrough whereby the steam in the other of said spaces will be forced through said hole upon the rotation of the rotor, a cylinder for receiving said steam and means for forcing the steam from the cylinder.

Copies of this patent may be obtained for five cents each, by addressing the "Commissioner of Patents, Washington, D. C."

2. In a rotary engine, a cylindrical casing, a rotor mounted therein on a shaft concentric with the casing, the rotor including oppositely extending substantially semi-cylindrical sections fixedly mounted on the shaft, the outer edges of said sections bearing against the inner face of the casing and being so constructed that gradually increasing spaces are provided to each side of the rotor, a plate, having a hole therethrough, slidably mounted in the casing and bearing against the face of the rotor, a piston secured to the outer end of said plate, a cylinder inclosing said piston, a valve mounted on said piston for closing the hole in the plate and resilient means for maintaining the plate in contact with the face of the rotor.

3. In a rotary engine, the combination with a casing having an eccentric rotor therein, of means for conveying steam into the casing to one side of the rotor, a plate extending within the casing and engaging the rotor, a steam receiving member mounted on and in communication with said casing, means operable by the steam to allow the same to escape into the receiving member, and means operable by the rotor to force the steam from said receiving member.

In testimony whereof, I affix my signature, in the presence of two witnesses.

ANTHONY V. WEBER.
